UNITED STATES PATENT OFFICE

ORLANDO D. SPALDING, OF EAU CLAIRE, WISCONSIN.

GRAIN-ELEVATOR.

SPECIFICATION forming part of Letters Patent No. 268,743, dated December 5, 1882.

Application filed April 9, 1881. Renewed June 8, 1882. (No model.)

To all whom it may concern:

Be it known that I, ORLANDO D. SPALDING, a citizen of the United States, residing at Eau Claire, in the county of Eau Claire and State of Wisconsin, have invented certain new and useful Improvements in Grain-Elevators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, in which—

15 Figure 1 is a vertical section. Fig. 2 is a top view with top removed. Figs. 3, 4, 5, and 6 are detailed sections.

This invention relates to grain-elevators.

The invention consists in the construction 20 hereinafter described.

In the drawings hereto annexed, A is the pit, B the basement, and C the ground-floor, of a grain-elevator. Rising from the floor at the walls of the building is the series of posts 25 D, their number being determined by the number of bins to be used, these posts resting on the sills d.

E is the truss-hoop, which passes around the inside of the building and rests on top of 30 the posts snug against the walls. This hoop is made in sections E', their ends e coming together at each post D. At these ends e these sections are enlarged, forming an inward offset, e', having the shoulder z.

35 F is a plate or tie, having offsets f f and shoulders y y, and of a shape to fit the abutting ends of the hoop-sections E', to which they are held by bolts f'. This makes a firm and strong hoop passing around the building, 40 said hoop occupying only a portion of the tops of the posts.

G are the trusses, composed of the bottom beam, g, and two or more upper beams, g'. The lower beam, g, extends outward at the 45 sides from the upper beams, as shown at x, forming shoulders. These beams are held together by stirrups H, which are looped over the upper beams, clasping them snugly, and its arms h h, passing down through beam g, 50 are secured by nuts, tie-plate, or other like device. The lower ends, v, of these trusses rest on the posts D, and the abutting ends of the sections E', the bottom beam on the posts, the others on the hoop, as shown. These trusses

spring upward and inward from the hoop E, 55 and their inner ends, t, converge to and are fastened to an inner hoop, I. This hoop is composed of sections I', which are made of beams bolted together, the meeting ends of the sections coming at the ends of the trusses 60 to which they are secured.

K are the floor-joists for the bins, upon which the flooring of the bins is to be laid, their ends being made fast to the lower beams, 65 g, upon shoulders x.

L is the pipe for the elevator, M the partitions between the bins, and N the outside walls of the structure; N', the walls of the pipe. Up and down these walls N' N runs the studding P, to which is secured the lining 70 Q of the bins at the outside.

S are braces running from the outer to the inner walls, and T the cross-braces connected to the braces S and to the partitions between the bins, said braces T being held to the studding m of the bins. 75

It is the elevator, passing from the pit to the top of the building, at which latter place are to be chutes for conducting the grain to the bins, these latter having discharge openings 80 for removing it when desired. This building is to have a taper upward, being smaller at top than at bottom, whereby it is stronger and better able to resist pressure, the bulk of the storage being below the middle. The construction described furnishes a building which is strong and convenient, doing away with much of the timber and material now in use. The floors of the bins are firm, and the structure resists the downward pressure, and the 85 bracing counteracts the side strain. By dispensing with the usual supporting-posts below plenty of room is obtained for working, handling, &c.

What I claim is—

1. A grain-elevator tapering upward, as described.

2. The combination of the outer and inner hoops and the connecting-trusses, substantially as described.

3. In a grain-elevator, the bins having the two sets of braces, as described.

In testimony whereof I affix my signature in presence of two witnesses.

ORLANDO D. SPALDING.
